UZARIGENIN GLYCOSIDES

Andor Fürst, Basel, Werner Meier, Binningen, and Kuno Meyer, Basel, Switzerland, Camilo A. R. Gavilanes, Las Palmas, Canarias, Spain, and Richard Rees, Los Angeles, Calif., assignors to Hoffmann-La Roche Inc., Nutley, N.J., a corporation of New Jersey
No Drawing. Filed Mar. 1, 1961, Ser. No. 92,469
Claims priority, application Switzerland Mar. 4, 1960
4 Claims. (Cl. 260—210.5)

The present invention relates to processes for obtaining cardioactive glycosides from *Digitalis canariensis L.* var. *isabelliana* (Webb) Lindigner, hereinafter designated *Digitalis isabelliana*. More particularly, it relates to processes for obtaining crude extracts containing the main glycosides of this plant, and for isolating from said crude extracts two hitherto unknown uzarigenin glycosides.

The processes according to the invention comprise extracting leaves of *Digitalis isabelliana* with water and aqueous alcohol, precipitating ballast materials from the aqueous alcoholic solution, extracting the thus purified aqueous alcoholic solution in turn with ether, chloroform, and chloroform/alcohol mixture consisting of one part by volume of alcohol and four parts by volume of chloroform, isolating the active materials which have passed into the chloroform/alcohol mixture, and (if desired) isolating from the thus obtained crude extract, which contains uzarigenin glycosides and digitoxigenin glycosides, the two novel uzarigenin glycosides in the form of mixed crystals thereof.

Digitalis isabelliana (synonym: *Callianassa isabelliana*) employed as the starting material is a kind of digitalis, of exceptionally high activity, indigenous to Grand Canary Island. Thus, upon determination of toxicity according to Hatcher-Magnus, it has been found that a cold extract of the leaves of *Digitalis isabelliana* is considerably more toxic than corresponding extracts from *Digitalis purpurea* and *Digitalis lanata*.

It has been found that the unusually high activity of *Digitalis isabelliana* is due on the one hand to a glycoside content higher than the average, and on the other hand to the presence of hitherto unknown cardioactive glycosides. The highest activity of the various extracts obtained by the processes of the invention is exhibited by a 4:1 chloroform/alcohol extract, see above. In said extract are found the main glycosides of the plant. Upon removal of the solvents, the active material is obtained in the form of an amorphous, greenish-brown powder. The crude extract contains, as can be demonstrated by paper chromatography, at least five components having a positive Kedde reaction (violet-blue color reaction with dinitrobenzoic acid and alkali, characteristic for compounds of the cardenolide type).

It has been further found that two glycosides predominate in the crude extract. They are designated herein as Glycoside A and Glycoside B. These two glycosides can be obtained from the crude extract in the form of water-soluble mixed crystals having M.P. of about 270–276°. It has been found that Glycosides A and B contain uzarigenin as the aglycone.

The lethal dose of the above mentioned mixed crystals (as determined according to Hatcher-Magnus in cats by intravenous administration) is 0.45 ± 0.05 mg./kg., i.e. considerably below the lethal dose of uzarigenin glycosides mentioned in the literature, e.g. odoroside B, uzarin or cheiroside A.

By the action of the glucose-splitting enzyme strophanthobiase, glucose can be split off from Glycosides A and B (obtained as mixed crystals), whereupon there are obtained two uzarigenin monosides, hereinafter designated as Desgluco-glycoside A and Desgluco-glycoside B; the

2

latter can be separated from each other and obtained in crystalline form.

	Desgluco-glycoside A	Desgluco-glycoside B
5		
M.P. [η] _D ²⁰	241–244° –29.2±2° (c=1.12 in Methanol).	241–244° –17.2±2° (c=1.09 in Methanol).
Rf-Value	0.55 (in system chloro- form/formamide).	0.74 (in system chloro- form/formamide).

Upon hydrolysis, these two monosides can be split into the aglycone uzarigenin and the 2-desoxy sugar which still remains attached to the aglycone after the preceding fermentation. This desoxy sugar is D-(+)-digitoxose in the case of Desgluco-glycoside B.

Accordingly, the following formula is ascribed to Glycoside B:

The processes of obtaining crude extracts and mixed crystals, taught by the present invention, as well as the degradation reactions taught herein, can be illustrated schematically as follows:

In the mother liquors remaining after isolation of the mixed crystals from the crude extract, there can be found, in addition to residual amounts of the two Glycosides A and B, additional digitoxigenin glycosides. Thus, by the action of strophanthobiase, the following additional monosides are found:

	M.P.
Evatromonoside	210–213°
Digitoxigenin glucomethyloside	225–230°
Digitoxigenin allomethyloside	152–156°
Digitoxigenin glucomethyloside	222–224°

The crude extracts obtained according to the processes of the invention, the mixed crystals isolated therefrom, and the constituent glycosides thereof, are useful as medicinal agents, more particularly as cardioactive and diuretic agents.

The invention is further disclosed in the following ex-

ample, which is illustrative but no limitative thereof. Temperatures are in degrees centigrade.

Example

A mixture of 500 g. of pulverized leaves of *Digitalis isabelliana* and 800 ml. of water is heated to 60° and stirred at this temperature for 90 minutes. Then 800 ml. of ethanol is added, the mixture is stirred for an additional period of 90 minutes at 60°, and filtered. The residue is extracted first with 1000 ml. of 60% ethanol, then with 1000 ml. of 70% ethanol, and finally is extracted twice, each time with 1000 ml. of 90% ethanol. The various extracts are combined and concentrated in vacuo to a volume of 700 ml. The concentrate obtained is diluted with 700 ml. of ethanol, and the ballast materials are precipitated by addition of lead (II) hydroxide. After separating the precipitate, the aqueous alcoholic solution is treated with the quantity of hydrogen sulfide required to precipitate the lead, and the lead sulfide is filtered off. The thus purified extract is concentrated in vacuo to 500 ml. and extracted in turn with ether (total of 1.5 liters), chloroform (total of 2.5 liters), and a mixture of four parts by volume of chloroform and one part by volume of ethanol (total of 2.5 liters). The aqueous phase is then concentrated to 400 ml. and extracted with a mixture of two parts by volume of chloroform and one part by volume of ethanol (total of 4 liters).

In the following table are shown the quantities of substances obtained from the various extracts, as well as their respective toxicities according to Hatcher-Magnus.

	Amount	Lethal Dose
Ether Extract.....	2.2 g.....	3.50±0.55 mg./kg.
Chloroform Extract.....	1.7 g.....	0.75±0.05 mg./kg.
Chloroform/Alcohol Extract (4:1).....	20.2 g.....	4.34±0.50 mg./kg.
Chloroform/Alcohol Extract (2:1).....	4.3 g.....	More than 0.06 ml./kg., i.e., more than 112 mg./kg.
Aqueous residual solution.....	400 ml.....	

The crude extract (20.2 g.) isolated from the chloroform/alcohol mixture (4:1) is an amorphous greenish-brown powder, containing uzarigenin glycosides and digitoxigenin glycosides. As shown in the table, this crude extract exhibits higher activity than all the other fractions. Upon paper-chromatographic development (system chloroform/tetrahydrofuran/formamide 50:50:6.5 parts by volume, descending, Whatman No. 1 filter paper impregnated with formamide), it is found that at least five compounds having positive Kedde reaction are contained in the crude extract, the two uzarigenin glycosides A and B being predominant in quantity.

The two glycosides can be obtained in the form of mixed crystals from the above described crude extract as follows:

20.2 g. of crude extract is dissolved in 150 ml. of

acetone, the solution is concentrated in vacuo until cloudiness appears, and then is cooled in an ice bath for three hours. 4.3 g of a gray-green powder separates, having M.P. 282-284°. Upon recrystallization from aqueous methanol, there are obtained fine colorless needles having M.P. 270-276°. This product is a crystalline mixture of Glycosides A and B. It is water-soluble. The lethal dose determined according to Hatcher-Magnus is 0.45 ± 0.05 mg./kg. i.v.

10 By means of strophanthobiase, glucose can be split off from mixed crystals of Glycosides A and B isolated in the form of mixed crystals, whereupon there are obtained two monosides (Desgluco-glycoside A and Desgluco-glycoside B).

15 Upon hydrolysis with 0.05 N sulfuric acid in 50% methanol, these two monosides can be split up into the aglycone uzarigenin and to the 2-desoxy sugar linked directly to the aglycone. In the case of Desgluco-glycoside B, D(+)—digitoxose is thereby obtained.

We claim:

1. Water-soluble mixed crystals of two uzarigenin glycosides of *Digitalis canariensis L. var. isabelliana* (Webb) Lindinger, said mixed crystals having M.P. of about 270-276° and a toxicity of 0.45 ± 0.05 mg./kg. (cat, i.v. determined according to Hatcher-Magnus).

2. Uzarigenin monoside having M.P. of 241-244° C., $[\alpha]_D^{20} = 29.2^\circ \pm 2^\circ$ (c=1.12 in methanol), $R_f = 0.55$ (chloroform/formamide).

3. Uzarigenin-D-(+)-digitoxoside having M.P. of 241-244° C., $[\alpha]_D^{20} = -17.2^\circ \pm 2^\circ$ (c=1.09, methanol), $R_f = 0.74$ (chloroform/formamide).

4. A process for the preparation of cardio-active uzarigenin glycosides which comprises the steps of extracting leaves of *Digitalis canariensis L. var. isabelliana* (Webb) Lindinger with water and aqueous alcohol, precipitating ballast materials from the aqueous alcoholic solution, extracting the thus purified aqueous alcoholic solution in turn with ether, chloroform, and a chloroform/alcohol mixture consisting of one part by volume of alcohol and four parts by volume of chloroform, isolating the active materials which pass over into the chloroform/alcohol mixture, and isolating mixed crystals of uzarigenin glycosides from said active materials by dissolving said active materials in acetone, recovering a precipitate therefrom, and recrystallizing the precipitate from aqueous methanol to obtain mixed crystals of uzarigenin glycosides.
